(57) **CLAIM**

We claim the ornamental design for a vehicle component, as shown and described.

DESCRIPTION

FIG. 1 is a front, left perspective view of the claimed design, according to a first embodiment;

FIG. 2 is a rear, right perspective of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top view of FIG. 1;

FIG. 8 is a bottom view of FIG. 1;

FIG. 9 is a front, left perspective view of the claimed design, according to a second embodiment;

FIG. 10 is a rear, right perspective of FIG. 9;

FIG. 11 is a front view of FIG. 9;

FIG. 12 is a rear view of FIG. 9;

FIG. 13 is a left side view of FIG. 9;

FIG. 14 is a right side view of FIG. 9;

FIG. 15 is a top view of FIG. 9; and,

FIG. 16 is a bottom view of FIG. 9.

The ornamental design that is claimed is shown in solid lines in the figures. Broken lines formed by equal or substantially equal length dashes show unclaimed portions of the design and form no part of the claimed design.

1 Claim, 14 Drawing Sheets
